229,744

RANGE GRATE HOLD DOWN CLIP

Joseph J. Oletti, South Bend, Ind., assignor to D & G
Associates, Inc., Elkhart, Ind.

Filed Mar. 24, 1972, Ser. No. 237,999

Term of patent 3½ years

Int. Cl. D8—07

U.S. Cl. D8—259

Fig. 1

Fig. 2

Fig. 3

Fig. 4

Fig. 5

Fig. 6

FIG. 1 is a perspective view of a range grate hold down clip embodying the present design;

FIG. 2 is a top plan view;

FIG. 3 is a front elevational view;

FIG. 4 is an elevational view of the side opposite the side shown in FIG. 1;

FIG. 5 is a rear elevational view; and

FIG. 6 is a bottom plan view.

I claim:

The ornamental design for a range grate hold down clip, substantially as shown.
